ASH TRAY

Frederick Valentine Schnebel, Middle River, Md.

Application March 26, 1947, Serial No. 737,262

3 Claims. (Cl. 131—241)

1

This invention relates to ashtrays and more particularly to those suitable for the reception of ashes from cigarettes, cigars and the like of the tobacco family.

It is an object of the present invention to provide a new and improved type of tobacco ash tray, that will avoid one or more of the disadvantages and limitations of the previous art.

A further object of the herein-described invention is to provide a new and improved type of tobacco tray that will be neat and artistic in appearance, and while of a compact nature will have a relatively large capacity for the reception of ashes from cigarettes and cigars, which will be accumulated automatically in the particular portion of the device intended for the purpose.

Still another object of the invention is to provide a new and improved tobacco ash tray that will afford convenient handling for emptying, and while in use on a table have a stable set-up.

Other inventions in the same class conventionally take the form of a tray, and in such cases are easily upsettable, throwing ashes out on the table and surface on which they are placed, in direct opposition to their intended purpose. At the same time, the amount of ashes they can take is limited in quantity and is spread out over a wide flat surface in each. This arrangement enables the ashes to spill out more easily or be blown off the surface.

For a clearer understanding of the invention and other object it may have, reference is made to the appended drawings. These drawings together with the following description illustrate a particular form of the invention by way of example and not limitation, while the claims emphasize the scope of the invention.

In the drawings:

Fig. 1 is a side elevation of an ash-tray embodying this invention; and

Fig. 2 is plan view of Fig. 1 on a reduced scale.

Similar reference characters refer to similar parts throughout the drawings.

The structure shown in the drawings follows that of a scoop in general, in which 10 is a handle fastened to a disc-like back 11 at its middle. An arcuately formed shovel plate 12 is bent to conform with the lower periphery of the back 11 which it encompasses substantially half around and is secured thereto with rivets or screws 13 suitably spaced on the periphery. The shovel plate 12 tapers towards the front portion along the walls and to the pointed front. On these walls 14 at their upper edges, are located a pair of cigar or cigaret holders 15 bent into semi-

2

circular form and tapered towards the front and back of them. They are welded or otherwise secured at the middle to the edges of the walls, so as to extend an equal distance in and out of the shovel plate 12, as indicated in Fig. 2. The ashtray is so formed that a support of dual wire legs 16 is attached at the underside of the shovel plate 12 near its front end, and at such an angle that a three-aligned-point suspension will be provided. The three-point support consists of the legs 16, considered as one, the edge of the back with the plate 12 encompassing as the second and the end of the handle 10 is the third. This supporting arrangement tilts the shovel plate up the front at angle, with the back 11 apexing towards it at the bottom of the device.

The legs 16 terminate in turned up loops 17 that afford a safe and rounded footing for the legs where they rest on the surface on which the device is placed for use.

The ashtray in the form illustrated serves as an ornament as well as a utility, especially when constructed of bright copper or other suitable material of an attractive nature, and sufficiently fireproof to enable it to hold the hot ashes from a cigar or cigaret. The tilt of the shovel place 12 towards the back 11 causes the ashes to slide down to the angularly converging portion where the plate 12 and back 11 meet, and there accumulate in a heap. The handle 10 forms a support and is so unobstructed as to permit its picking up for dumping the ash contents. This dumping may be accomplished by lifting the whole device off the table and carrying it to another location for discharging, in which case the handle is the most convenient means by which it may be carried. Also the device could be dumped by raising the back of ash tray by the handle using the legs as a fulcrum on which to tilt it. The ash contents can thus be discharged into a pan or saucer without removing the device from the table. The pan may then be taken to another location for dumping. The cigar holders 15 serve their usual purpose, but are so placed that they may be used for lifting the ash tray by them if the user prefers. Likewise the legs 16 form an easy and accessible arrangement for lifting the ashtray. Another feature of the device is its lack of parts to interfere with its proper cleaning, and it is placed in an inverted position on the table, it may be used for other domestic purposes. This being made possible by the upwardly projecting legs 16 and handle 10, and the stable arrangement for holding the device relatively immovable on the

front rim of the shovel plate 12 and the upper edge of the back 11.

In this position it is unusual but none the less interesting. While the device resembles a conventional flour scoop, it is not one. The resemblance makes it much easier for a new user to appreciate how it may be used, and discharged.

While but one form of the invention is shown in the drawings and described herein, it is not desired to limit this application for Letters Patent to that particular form, as it is appreciated that other forms of the invention may be made that could employ the same principles and come within the scope of the following claims.

Having thus described the invention, what is claimed is:

1. An ash tray for cigars and the like comprising in combination, a shovel plate of semi-circular form curved and tapered towards its front end, holders for cigars supported on the edges of said plate and arranged to assume a horizontal position when said plate is normally placed, a back of disc-like contour having its peripheral surface partly encompassed by said plate and secured thereto, a handle extending rearwardly from said back with its end portion adapted to rest on a horizontal surface when aligned with the edge of said back resting thereon, and a support on the underside of said shovel plate for supporting the latter in a tilted position with said edge and end portion also in contact with said surface.

2. An ash tray of the class described compris-

ing, a shovel plate bent into the form of a scoop with a tapered front portion, a back for said plate for completing the scoop and for holding a portion of the scoop peripherally bound thereon, a handle extending at right angles to said back, and a leg member attached to the underside of said scoop to support it so said scoop will be tilted angularly from a horizontal surface on which the tray is supported, and will be held in such position by the horizontal alignment of the end of the handle, a portion of the back and plate and said member.

3. And a structure as described in claim 2 with the addition of holders for cigars mounted on the edges of said plate for holding cigars in a horizontal position thereon over the scoop, and said member having means formed thereon for providing a rounded contact on said surface.

FREDERICK VALENTINE SCHNEPEL.
